UNITED STATES PATENT OFFICE.

SAMUEL B. WILLIAMS, OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed March 22, 1924, Serial No. 701,006. Renewed April 5, 1926.

This invention relates to telephone exchange systems and more particularly to systems employing automatic switching apparatus for establishing connections.

5 An object of the invention is to intercept calls which are directed to certain lines or stations before the switches have fully operated to establish a connection and to route such calls in a different direction.

10 A feature of the invention relates to the provision, in a system employing switch controlling markers common to the selector switches and translators associative with the markers and switches, of means in the translators serving to intercept calls directed to certain lines and to cause the calls to be routed to an operator.

Another feature relates to a translator, common to the subscribers' lines for controlling the switches to make connection to such lines, wherein the lines are so represented that calls to one or more stations on one of said lines may be intercepted and directed to an operator.

25 Still another feature relates to the provision, in a system in which the called lines are divided in groups with a translator for each group governing the connector switches which make connection to said lines, of means in the translator whereby each line of that group is represented and whereby calls to any line may be intercepted independent of the connector switch having access to said line.

35 Another object of the invention is to divide the trunks incoming to a selector switch into groups and to provide for associating the marker for testing purposes with the particular group which contains the trunk over which a connection has been extended.

Another object of the invention is an improved method of giving the calling party a busy notification.

45 According to this latter object, a busy tone apparatus is associated with one of the selective switches and appearing in the contacts thereof, together with means for partially releasing the attempted connection to a called line when such line is busy and for reestablishing the connection through

said switch to seize the busy tone equipment.

Referring to the drawing, Figs. 1 to 12 inclusive when taken in the order illustrated 55 in Fig. 13 disclose a portion of a telephone exchange system embodying the features of this invention.

Fig. 1 shows diagrammatically a line switch in which calling lines appear, a district selector switch, a sender selector switch and a portion of one of the register senders.

Fig. 2 shows an incoming selector switch in which terminate trunks leading from the district selector shown in Fig. 1.

Fig. 3 shows a portion of one of the final or connector switches in which terminate the called subscribers' lines.

Figs. 4, 5 and 6 illustrate the registers of the sender partially shown in Fig. 1.

Fig. 7 shows a sender connector for connecting the register senders to the markers.

Figs. 8 and 9 illustrate one of the common markers, the function of which is to control the incoming and final switches.

Fig. 10 shows an incoming frame connector for connecting the markers to the frames of the incoming selectors.

Fig. 11 shows a translator connector, the purpose of which is to connect any of the 80 markers with any of a number of final translators.

Fig. 12 illustrates one of the final translators, the function of which is to cooperate with the marker in the control of the 85 final switches.

General description of the circuits and apparatus.

The calling subscribers' lines 100 terminate in line switches 101 which operate to extend said lines to trunks 102 leading to district selector switches 109. Trunks 102 also appear in sender selector switches 103 which operate to select an idle register sender 107 and to associate the same with a calling subscriber's line.

The district selector switches 109 may extend the calling lines to distant offices or to trunks 110 which extend to incoming selectors 200 located in the same office. The incoming selector switches 200 in turn have

access to groups of trunks which lead to different groups of final connector switches 300 which in turn have access to the called subscribers' lines.

- 5 The line switches 101, sender selectors 103, district selectors 109, incoming switches 200 and connector switches 300 are of the co-ordinate type such as generally shown and described in the copending application of 10 C. L. Goodrum and J. N. Reynolds, Serial No. 486,442, filed July 21, 1921, Patent No. 1,515,735, granted Nov. 18, 1924.

Inasmuch as the present invention is concerned particularly with the operation and control of the incoming and final switches 200 and 300, it has not been considered necessary to go into the details of the operation of the line switch, the district selector, the sender selector or the subscriber's register 20 sender. The operation of these switches and of the register sender may be substantially the same as that fully described in the patent to S. B. Williams, No. 1,517,331, granted Dec. 2, 1924. Wherever detailed 25 operations are referred to hereinafter and are not fully illustrated, reference is made to said application for an understanding thereof.

- 30 The total number of incoming selector switches 200 may be divided in a number of groups each of which receives trunks from the district selector switches 109. For each of these groups there may be provided a frame connector 1000 which serves to connect any of the incoming markers to the incoming frames of this particular group. In order that the marker may select and operate the proper frame connector it receives certain information from the register sender 35 for this purpose. The trunks 110 which have access to a particular group of incoming frames, may be segregated on certain vertical rows of the district selectors 109. The same is true of trunks 110 leading to 40 other groups of incoming frames. Therefore, when the marker is connected to the outgoing trunk group, at the time switch 109 is operating a circuit may be closed from the contact of magnet 116 through the 45 marker 115 to operate relay 108 in the sender. An indication is thus given to the sender relative to the particular group of incoming selector switches that is to be involved in establishing the connection. During 50 the time the sender is associated with the incoming marker shown in Figs. 8 and 9 this information is transferred to the latter mechanism.

55 The subscribers' lines considered as called lines are divided into a suitable number of groups. If it is assumed that the exchange comprises 10,000 lines, it may be convenient to divide these into five groups of 2,000 lines each. For each group of 2,000 lines a suit-

able number of connector switches 300 are 65 provided for making connection therewith. Furthermore, each group of 2,000 lines is provided with a final translator 1200 which is common to all of the connector switches of the group and serves to selectively operate the same. The translator 1200 is made up of forty multi-contact relays 1208, 1212, 1213 and so forth. Each of these relays has contacts individually representing fifty different subscribers' lines. The grid wires 70 with which these relays make contact are divided into ten different sections 1214, 1215 and so forth, each section representing five different lines for each relay. Since there are forty relays in the translator, twenty of 75 these represent the lines in the even thousand and the other twenty represent the lines in the odd thousand. Two relays in each thousand 80 represent the lines of a given 100 therein, both in the even and odd thousands. 85

There being ten hundreds in each thousand, ten relays 1211, 1216 and so forth are provided. Accordingly, each relay represents a given hundred in both the even and odd thousand. The relays 1217 and 1218 90 determine the value of the units digit of the wanted line. For instance, if the units digit is less than five, one of these relays operates, whereas, if the units digit is greater than four, the other relay operates. 95

The value of the tens digit is determined by one of tens relays 1209, 1210 and so forth.

Thus with the proper hundreds relay operated, with the proper one of the relays 100 1217 and 1218 operated and by knowing whether the thousand is even or odd, the particular one of the multi-contact relays 105 of the translator is selected which represents the fifty lines in the proper thousand, in the proper hundred, having units digits greater than four or less than five, as the case may be. By thereupon operating the proper one of the tens relays 1209, 1210 and so forth, the selection is reduced to the particular five lines including the wanted subscriber's line. 110

115 The connector switches 300 comprises five sets of horizontal links 311, 312 and so forth. The subscribers' lines appear in the vertical 115 rows of contacts 303, 304 and so forth, each line appearing before all of the horizontal links in the section. Thus, the vertical row of contacts 303 includes five different lines and two of these vertical rows together make up the tens lines, each having a different one of the ten units digits. It will be noted that this arrangement corresponds with the representation of the subscribers' lines in the translator 1200. 120

125 The trunks outgoing from the incoming selector switches 200 appear in vertical rows 203, 204 and so forth, each group of trunks

being multiplied so that each trunk has access to a single horizontal link in each of the several sections of links. These trunks appear in the connector switches 300 in vertical rows of contacts 301, 302 and so forth.

When the marker has been associated with the proper final translator through the connector 1100 the connecting device 1202 is operated to extend the marker test leads to the proper connector 300 of the group. There is furthermore provided a connecting device 1201 which is controlled by the units digit and which serves to connect the marker test leads only to the particular one of the five horizontal sections 311, 312, of the connector switch in which appears the called subscriber's line.

Referring again to the incoming selectors, these switches are divided into several horizontal sections 832, 833, etc. Each section comprises a separate group of horizontal links, and the incoming trunks are multiplied to appear before the horizontal links of only one section. For instance, the section 832 includes the links 205 and 206, and a group of incoming trunks including the trunk 110 appears only before the horizontal links of this section.

When the marker is associated with the incoming selector switch, as will be hereinafter described in detail, arrangement is made whereby such marker will be connected only to the horizontal links of the section or group in which appears the incoming trunk over which the connection has been extended. The reason for this is obvious. If, for instance, the incoming connection has been extended over trunk 110, it is desirable that the marker be associated with the section 832 in order to test the links 205, 206, etc., inasmuch as these are the only links which can be involved in the further extension of the incoming trunk.

The selective association of the marker with the proper one of the different groups of horizontal links and the incoming switch is accomplished by means of the incoming frame connector 1000. This frame connector is made up of a number of multi-contact relays 1001, 1029, etc. Each of these relays in addition to identifying a particular incoming frame 200, also identifies a given section of horizontal links or the corresponding group of trunks incoming to said frame. The relay 1001 represents the frame 200 and also represents the group of incoming trunks appearing in the section 832 of horizontal links. Therefore, whenever a connection is extended over one of the trunks 110 appearing in the section 832, the relay 1001 is operated to connect the marker test leads to the test conductors of the horizontal link circuits 205, 206, etc.

The multi-contact relay 1029 represents

the same frame 200, but this relay is only operated whenever a connection is extended over one of the incoming trunks which appears in the horizontal links of the section 833. In a similar manner, other groups of horizontal links and other identifying relays in the frame connector 1000 may be provided.

In order to intercept calls made to any particular line, there is provided a set of relays 1203. By connecting these relays arbitrarily to the necessary points on the distributing frames 1220 and 1221, the proper relay or combination of relays may be operated whenever a call is directed to the line in question.

In the case of party lines, these relays may be operated in combinations such that calls made to any party or parties on any line may also be intercepted. The necessity for this service occurs where the lines are discontinued, where all of the stations have not been installed, and for various other reasons.

Detailed description of the operation.

Extension of a connection to a party line.—It will be assumed that the subscriber of line 100 wishes to hold a conversation with the subscriber at station J on the party line 318, and that the designation of the desired station is COR 2234-J. Accordingly, the calling subscriber initiates the call, whereupon the line switch 101 operates to extend the line to an idle trunk 102 leading to the district selector 109 and whereupon the sender selector switch 103 operates automatically and extends the subscriber's line to an idle register sender 107.

The calling subscriber now transmits impulses to the sender representing the office code designation COR. These impulses are received in the sender and are recorded on the first three registers 600, 601, and 602 of the register mechanism. The first series of impulses representing the letter "C" is recorded on the register 600 by placing ground potential on the proper conductors of the group 111 leading from the sender 107. The conductors 111 are extended to the relays of the register 600 by means of the cut-in relay 603.

The second series of impulses representing the letter "O" cause the operation of the register relays 601, the cut-in relay 604 having operated by means of a circuit completed in the sender and extending through the front contact of relay 606.

After this, relay 607 operates, followed by the operation of relay 605, and the third series of impulses representing the letter "R" is recorded on the register 602.

In a similar manner, the four numerical digits and the stations digit J (the latter being represented by five impulses) are transmitted to the sender and recorded on

- the registers 500, 502, 400, 401 and 402. It will be assumed that the thousands digit 2 causes the operation of the register relay 503 of the thousands register 500; that the hundreds digit 2 causes the operation of relay 508; that the tens digit 3 causes the operation of relays 403 and 404; that the units digit 4 causes the operation of relay 408; and that the stations digit J causes the operation of relay 409. Relay 503 in operating, operates the relay 504 in a circuit from battery through the winding of relay 504, inner right contact of relay 503, outer right back contact of relay 505, left contact of relay 503, thence over the operating conductor 506, to ground. It will be understood, of course, that the register relays having operated, may be locked in any suitable manner.
- 20 The office registers shown in Fig. 6 upon receiving the office code, are connected to an outgoing marker 115 which governs the operation of the district selector switch 109 to extend the subscriber's line over an idle
- 25 trunk 110 leading to the proper group of incoming selector switches 200.
- When all of the digits have finally been received and recorded in the register sender, the sender causes ground potential to be placed upon conductor 112, which operates the relay 701 of the sender connector 700. The relay 701 locks in a circuit from battery, through the winding of relay 702, upper winding of relay 701, to ground over conductor 112. Relay 702 also operates and prevents the subsequent operation of another relay similar to relay 701 in case a second sender attempts connection to a marker. The multi-contact relay 703 is now operated
- 40 in a circuit from battery, through its winding, lower contact of relay 701, outer back contact of relay 704 to ground at the contact of relay 702. Relay 703 locks through its contact to ground at the left contact of relay 702.
- Relay 702 operates the relay 706 which relates to the first idle marker (it being assumed that the marker represented by relay 709 is busy at the time). The circuit for relay 706 may be traced from ground, through the inner right contact of relay 702, back contact of relay 704, front contact of relay 710, lower contact of relay 709, back contact of relay 705, lower winding of relay 706, to battery through the contact of relay 708. Relay 706 operates and locks in a circuit from battery, through the winding of relay 708, contact and upper winding of relay 706, conductor 711, to ground at the contact of relay 702. Relay 708 also operates in this circuit. Relay 706 operates the relay 704 in a circuit from battery, through the winding of the latter relay, upper contact of relay 706, to ground at the contact of relay 708. The multi-contact relay 707 is next operated
- 45 to extend the various leads from the sender to the idle marker. The circuit for relay 707 may be traced from battery, through the winding thereof, contact of relay 706, to ground at the contact of relay 708. Relay 705 also operates in parallel with relay 707.
- 50 As soon as the sender is connected to the marker, the holding relay 900 is operated in a circuit from battery, through the winding thereof, conductor 901, through the connector 700, conductor 902, to ground in the sender. Relay 900 locks in a circuit through its winding and contact, right back contact of relay 903, to ground at the inner left contact of slow relay 904.
- 55 The record of the thousands, hundreds, tens, units and stations digits and of the particular group of incoming switches involved, is now transferred from the sender to the marker. First considering the record of the group of incoming selectors to which the trunk 110 extends, it will be noted that this trunk appears in the district selector 109, in the row controlled by the vertical magnets 116. Therefore, when the magnet 116
- 60 operates during the association of the marker 115 with the selector switch, it operates the relay 108 in the sender. With relay 108 operated and with the sender connected to the marker as explained, a circuit is established for operating the frame test relay 806 and may be traced from battery, through the winding of said relay, conductor 807, thence over conductor 712, to ground at the contact of relay 108. The function of relay 806 will be described hereinafter.
- 65 Since the relay 504 of the register 501 is operated in the sender, relay 808 is energized in circuit from battery, through the winding of said relay, conductor 812, thence over conductor 713, front contact of relay 504 and returning over conductor 510, thence to conductor 714, inner right contact of relay 905, conductor 909, outer left contact of relay 910, right back contact of relay 911, inner right contact of relay 912, conductor 913, to ground at the contact of relay 900. Since the remaining relays 511, 512 and 513 of the register 501 remain deenergized temporary circuits are closed for operating relays 840, 841 and 842, which may be traced through the windings of these latter relays, thence through the sender connector 700, over conductors 515, 516 and 517, through the back contacts of relays 511, 512 and 513, respectively, thence over conductor 518, conductor 715, back contact of relay 809, normal contact of relay 810, conductor 811, thence to ground over conductor 714, as previously traced.
- 70 With the hundreds register relay 508 operated a circuit is closed for relay 813 traceable from battery through the winding of said relay, conductor 824, thence to conductor 716, front contact of relay 508, thence to

the grounded conductor 510. Since the remaining relays of register 502 are deenergized, relays 812, 814 and 815 are operated temporarily in circuits traceable through the 5 back contacts of the relays of register 502 and thence to ground over conductor 518.

In the manner similar to that already explained the tens register relays 816 and 817 are operated in circuits traceable through 10 the front contacts of relays 403 and 404 and relays 818 and 819 are operated in circuits through the back contacts of the remaining two relays of register 400, relay 822 is operated through the front contact of relay 408 15 and relays 820, 821 and 823 are operated through back contacts of the remaining three relays of register 401, and relay 829 is operated through the front contact of relay 409 and relays 826, 827 and 828 are operated 20 in circuits through the back contacts of the remaining relays of the station's register 402.

When all of the register relays in the marker have operated, relay 809 is operated 25 in a circuit from battery through its winding, thence through series contacts of all the relays in registers 804, 803, 802, 801 and 800 to ground. Relay 809 locks through its lower contact, normal contact of relay 810 30 to the grounded conductor 811. Relay 809 operates the relay 810 in an obvious circuit. Relay 810 opens the locking circuit of relay 809 and closes a locking circuit for itself. Relay 809, in operating, opens the circuits 35 of all the register relays in the marker which do not correspond to the operated register relays in the sender, and these relays, thereupon, become released. Relay 809 becomes deenergized.

40 *Connection of the marker to the incoming selector frame.*

The frame connector 1000 is next operated to associate the marker with the group of 45 incoming frames and also with the particular incoming selector frame 200 to which the calling line has been extended. For this purpose relay 1004 is operated in a circuit from battery through its winding, conductor 50 1007, inner right back contact of relay 805, right front contact of relay 806, conductor 826, upper contact of relay 810 to the grounded conductor 811. It will be noted that the relays 806 and 805 may be operated 55 in different combinations to select other conductors similar to the conductor 1007 leading to other frame connectors (not shown). Relay 1004 operates the relay 1005 in a circuit traceable through the back contact of relay 1008, back contact of relay 60 1002 to ground at the back contact of relay 1003. Relay 1005 operates relay 1003 in a circuit from battery through the winding of relay 1003, right back contact of relay 1002, 65 lower contact of relay 1005, conductor 1009,

outer right contact of relay 912 to the grounded conductor 913. Relay 1005 being slightly slow to release, does not retract its armatures while relay 1003 is operating. Relay 1003 closes a circuit from battery 70 through the upper winding and contact of relay 1005, thence through the winding of relay 1002 to ground at the front contact of relay 1003. Relay 1002 operates and locks 75 through its winding and front contact to the grounded conductor 1009. The circuit of relay 1003 is open when relay 1002 operates, but relay 1003, being slow to release, does not retract its armature until after relay 1002 has had time to close its front contact. 80 The multi-contact relay 1006 is then operated in a circuit from battery through its winding, upper contact of relay 1005, left front contact of relay 1002 to ground at the back contact of relay 1003. The relay 85 1006 is individual to the marker shown and serves to connect the conductors from there to the grid wires of the frame connector 1000.

The next operation to take place is the energization of the vertical magnet 209 controlling the vertical row of contacts 201 on the incoming selector switch 200 in which appears the trunk 110. A circuit for this purpose may be traced from grounded conductor 1009, contact of relay 1006, conductor 1011, normal contact of relay 914, conductor 915, thence over conductor 717, thence through the sender and sender selector switch 103, over one of the talking conductors through the district selector 109 to operate a relay in the trunk circuit 110 such as the relay 113. The manner in which this circuit is completed from the marker through the sender connector and thence through the sender and sender selector 100 switch is fully described in detail in the above-mentioned patent to S. B. Williams, 105 No. 1,517,331, granted Dec. 2, 1924. The relay 113 applies ground potential to conductor 114 which extends through the winding of 110 the magnet 209 to battery. The magnet 209 rotates the bar 207 and prepares the contacts in the vertical row 201. The multi-contact relay 1001 individual to the incoming selector 200 is also operated in a circuit from 115 battery through the winding of said relay, conductor 1012 to ground through the contact of relay 113. Relay 1001 connects the grid wires of the frame connector 1000 to the leads extending to the incoming switch 200. Magnet 209 operates the relay 914 in a circuit from battery through the winding of said relay, conductor 916, through the connector 1000 to ground at the contact of magnet 209. Relay 914 closes locking circuits for the magnet 209 and relay 1001. 120 These circuits may be traced from battery, through the winding and contact of magnet 209 and in parallel from battery through the winding and contact of relay 1001, 125 130

thence over conductor 1013, through the connector 1000, conductor 1014, contacts of relay 914, conductor 1011 through the lower contact of relay 1006 to the grounded conductor 1009.

Connection of the marker to the final translator.

- The next step in the process is to associate the marker with the particular one of the five final translators which has control over the group of final switches reaching the group of 2000 lines containing the called line 318. The selection of the proper final translator is determined by the thousands digit which, it will be remembered, is recorded on the marker register 800. Therefore, when relay 1005 operates a circuit is closed for operating the relay 1108 which is individual to this particular marker at the connecting device 1100. This circuit may be traced from ground through the back contact of relay 1003, front contact of relay 1002, uppermost contact of relay 1005, conductor 1010, inner upper contact of relay 810, right front contact of relay 808, outer right back contact of relay 840, conductor 827, winding of relay 1108 to battery. Relay 1108 closes an operating circuit for relay 1105 including the contacts of relays 1106 and 1107. Relay 1105 operates the slow-release relay 1107 in a circuit through the winding of the latter relay, left contact of relay 1106, left contact of relay 1105, conductor 1110, right back contact of relay 911, thence through the grounded conductor 913. Relay 1105 being slightly slow to release, does not retract its armatures while relay 1107 is operating. Relay 1107 closes a locking circuit for relay 1105 and an operating circuit for relay 1106. Relay 1106 operates and locks through its left front contact, left contact of relay 1105 to ground over conductor 1110. Relay 1107 thereupon releases. The multi-contact relay 1103 is now operated in a circuit through its winding, contact of relay 1105, front contact of relay 1106 to ground at the back contact of relay 1107. Relay 1103 connects the various leads from the marker to the conductors extending to the final translator shown in Fig. 12.

The operation of the final translator will next be discussed. Inasmuch as the hundreds digit of the wanted line is 2, the hundreds relay 1211 is operated in a circuit from battery through its winding, conductor 1222, through the connector 1100, conductor 1111, inner right-hand contact of relay 812, inner right front contact of relay 813, inner right back contacts of relays 814 and 815 to the grounded conductor 826. Since the units digit is 4 and, consequently, less than 5, the relay 1218 is operated in a circuit from battery through the winding to the horizontal links of the group 311

of said relay, thence through the connector 1100, conductor 1112 to ground at the back contact of relay 823. Since the thousands digit is 2 and even the multi-contact relay 1208 is operated in a circuit from battery through the winding thereof, lowermost contact of relay 1211, inner contact of relay 1218, thence through the connector 1100, conductor 1113, right back contact of relay 842, inner upper contact of relay 810, to ground over the conductor 1010.

Due to the fact that the tens digit of the wanted number is 3, the relay 1209 is energized in a circuit from battery through the winding thereof, through the connector 1100, conductor 1114, inner right front contacts of relays 816 and 817, inner right back contacts of relays 818 and 819 to the grounded conductor 826.

The translator has thus been operated and a selecting circuit is now completed there-through for selecting and operating the vertical operating magnet 316 on the final selector 300 which controls the particular vertical row of contacts 303 in which appears the called subscriber's line 318. The circuit for this purpose may be traced from ground, over conductor 826, thence over conductor 828, through the connector 1100, conductor 1223, lowermost contact of relay 1209, contact of relay 1208, conductor 1224, winding of the magnet 316 to battery. Magnet 316 rotates the bar 320 and prepares all contacts in the vertical row 303. Magnet 316 also operates the relay 1204 which is individual to the final connector frame 300 and which serves to connect certain leads from the translator to said frame. The circuit for this purpose may be traced from battery through the winding of relay 1204, back contact of relay 1225, conductor 1226, inner contact of magnet 306 to ground over conductor 1224 as previously traced.

Magnet 316 and relay 1204 lock in circuits 110 from battery through the winding and inner contact of magnet 316, thence through the lower contact of said magnet and in parallel thereto from battery, through the winding of relay 1204 and thence over conductor 1226, through the lower contact of magnet 316 and thence over the conductor 321, conductor 1227, conductor 908, right back contact of relay 907, outer right back contact of relay 906, outer left contact of relay 910, right back contact of relay 911, inner right contact of relay 912 to the grounded conductor 913.

Inasmuch as the units digit of the wanted line is 4 and the line appears in the section 311 of the connector switch 300, it will be necessary to operate the multi-contact relay 1206 of the connecting device 1201 in order to connect the testing leads from the marker to the horizontal links of the group 311

in exclusion to other groups in the connector switch. The circuit for relay 1206 may be traced from battery through its winding, conductor 1228, through the connecting device 1100, conductor 1115, right front contact of relay 822, right back contacts of relays 821 and 820 to the grounded conductor 826. Relay 1206 locks through its winding and contact to the grounded conductor 1227.

Connection of the marker to the group of trunks interconnecting the incoming and final switches.

15 Inasmuch as the incoming switches have groups of trunks leading to the final switches of the several terminal line groups, it is essential that the marker be connected to the particular group of trunks which 20 leads to the final selector 300 containing the called subscriber's line.

The identity of the incoming selector group may be had from the incoming frame connector 1000 and the identity of the group connector 1100. Accordingly, the 25 identity of the final switches may be had from the translator connector 1100. Accordingly, the multi-contact relay 1015 is operated in a circuit from battery through its winding, contact of relay 1016, conductor 1017, 30 through the connector 1100, conductor 1116, returning over conductor 908 to ground. Relay 1015 is individual to the group of trunks including the trunk 213 and serves 35 to connect the marker testing equipment to the sleeve conductors of these trunks. Relay 1015 operates the relay 1019.

Testing the trunks and links and called line.

40 The marker is provided with a series of testing relays 920 comprising a sufficient number of relays for testing the horizontal links of the incoming selectors, the trunks outgoing therefrom, and the horizontal 45 links of the final selectors. The double-wound relays 921, 922, 923, etc. each have a winding for testing a horizontal link in the incoming switch and a winding for testing the trunk which has access to such 50 link. Either winding is sufficient to operate the relay and both windings will also operate the relay. The relays 924, 925, etc., pertain to the corresponding horizontal links in the connector switch. Assume, first, that 55 the link 205 of the incoming switch 200, the first trunk 213 and the link 305 of the connector switch are all simultaneously busy. A circuit is, therefore, completed from battery through the left winding of 60 test relay 921, innermost back contact of relay 927, through the connector 1000, conductor 1020 to the grounded sleeve conductor of the link 205. Another circuit is 65 closed from battery through the right winding of relay 921, next to the inner back

contact of relay 927, inner right back contact of relay 928, conductor 929, through the connector 1100, conductor 1117, through the relay 1015, conductor 1022 to the grounded sleeve conductor of trunk 213. 70 The link 305 also being busy, a circuit is closed for operating relay 924 which may be traced from battery through the outer left contact of relay 930, winding of relay 924, conductor 931, contacts of relay 1019, conductor 1023, through the connector 1100 conductor 1118, through the connecting device 1201, through the connecting device 1202, conductor 1229 to the grounded sleeve conductor of the link 305. Had the link 80 205 and the trunk 213 been idle the busy condition of link 305 would cause the operation of relay 924, which in turn, would cause the operation of relay 921. The operating circuit for relay 921 in this case 85 may be traced from battery through its right winding, inner contact of relay 924, outer right back contact of relay 930, conductor 932 to ground at the inner right contact of relay 900. The relay 921, in 90 operating extends the start conductor 933 on to the next test relay 922 which may or may not be energized according to the condition of the corresponding links and 95 trunk.

If, however, the first link 205, trunk 213 and the link 305 are all idle at the time, the test relay 921 remains deenergized. The magnet 212 which controls the 100 vertical row of contacts 204 in which appear the trunks of the selected group is also operated at this time. The circuit for this purpose may be traced from battery, through the winding of said magnet, conductor 215, through the connector 1000, conductor 1024, through the connector 1100, conductor 1119, contacts of relay 1015, conductor 1230, contacts of relay 1206, contacts of relay 1204, conductor 1231, through the connector 1100, conductor 1120, contacts of relay 1019, conductor 1121 to the grounded conductor 908. The magnet 212 rotates the bar 216 and prepares the contacts in the vertical row 204.

The magnet 212 operates the relay 930 in 115 a circuit traceable from battery through the winding of said relay, contact of relay 903, conductor 934, contact of magnet 212 and returning through the connector 1000 to ground over conductor 1009. Relay 930 operates the relays 927, 928 and 905. A circuit for this purpose may be traced from the grounded conductor 932, through the outer right front contact of relay 930, thence in parallel through the winding relay 927 and through the inner right contact of relay 910, conductor 933, back contact of relay 935, left back contact of relay 921, winding of relay 928, winding of relay 905 to battery.

125 During the foregoing operations, a test is 130

also being made of the condition of the called subscriber's line. At the time the connecting devices 1202 and 1201 are operated, the magnet 310 is energized in a circuit from battery through its winding, thence through contacts of connecting devices 1202 and 1201 to the grounded conductor 1227. Magnet 310 operates the common test link 307 which makes connection with the sleeve conductor 5 of the called line 318. When relay 930 later operates, a test circuit is closed from battery through the winding of relay 911, front contact of relay 930, outer right back contact 10 of relay 910, left contact of relay 936, conductor 937, contact of the connector 1100, conductor 1232, contact of relay 1204, conductor 322, over the test link 307 to the sleeve conductor of line 318. Assume the line 318 to be idle at the time relay 911 fails to 15 operate.

With the test relay 928 operated, as above explained, a circuit is closed for operating the vertical magnet 315 on the final selector switch in the contacts of which the trunk 213 appears. This circuit may be traced from the grounded conductor 908, thence through the outer right contact of relay 928, conductor 939, contacts of relay 1019, conductor 1025, through the connector 1100, conductor 1122, through the relay 1015, conductor 1233, through the relay 1204, winding of magnet 315 to battery. Magnet 315 rotates the bar 313 and prepares the contacts in the vertical row 301. The magnet 315 also causes the operation of the horizontal magnets 217 and 309 to complete the connection to the called line. The circuit for magnet 217 may be traced from battery to the right winding of said magnet, conductor 218, through the frame connector 1000, conductor 1026, outer left contact of relay 928, conductor 940, through the connector 1100, conductor 1123, through the connector 1202, contact of magnet 315, conductor 1226, contact of magnet 315 to ground over conductor 321. Magnet 217 operates, rotates the bar 220 and establishes connection between the trunk 110 and the trunk 213 through the medium of link 305.

The circuit for magnet 309 may be traced from battery, through the right winding thereof, conductor 323, through the connector 1202, through the connector 1201, thence through the connector 1100 to conductor 1124, thence through the relay 1019, conductor 1027, outer left contact of relay 928 and thence to ground over conductor 940 as traced. Magnet 309 rotates the bar 314 and the trunk 213 is connected to the line 318 through the medium of the idle link 305.

When magnet 217 operates it closes the locking circuit for itself from battery through both windings thereof, thence through contacts of the switch 200 to the grounded sleeve conductor of the trunk 110.

When the switch 200 operates relay 324 is energized in a circuit from battery through its normal contacts, right winding of relay 324, sleeve conductor 327, through contacts of the switch 200 to the grounded sleeve conductor of trunk 110. Relay 324 operates and closes the holding circuit from battery through the winding of relay 325, right front contact of relay 324 to the grounded conductor 327. Relay 325 also operates in this circuit and applies ground potential to the sleeve conductor 328. When magnet 309 operates it locks through both its windings to the grounded conductor 328.

In any suitable manner, ringing current 80 may be applied to ring the subscriber's bell whereafter the parties may hold conversation over the established connection.

Release of the sender and marker.

At the time the test is made of the links and trunks a circuit is completed for initiating the restoration of the sender. This circuit may be traced from the grounded conductor 908, thence through the outer right contact of relay 905, conductor 941, thence through the sender connector 700 to the register sender 107. The closure of this circuit may serve to operate a relay in the sender to bring about disconnection of the sender from the marker in the manner explained in the patent to S. B. Williams No. 1,517,331, granted Dec. 2, 1924. Relays 701 and 702, in releasing, due to the disconnection of the sender, cause the release of relay 703. Relay 705, however, remains energized in a circuit through its upper winding, thence over conductor 718 to the grounded conductor 913.

At the time ground is applied to conductor 328 a circuit is completed for operating the marker release relay 903. This circuit may be traced from battery, through the winding of said relay, inner right front contact of relay 928, conductor 929, thence as previously traced to conductor 1022, thence to a grounded conductor 328. Relay 903 releases relays 900 and 930 and these relays, in turn, remove ground from the various holding conductors to permit the restoration of the marker and associated equipment.

Called subscriber's line tests busy.

In case the called line is busy at the time the test is made, the busy test relay 911 is operated in the circuit heretofore traced. Relay 911 at its right contact causes the release of the operated test relays 920, the marker connector 1100, the relays 1019 and 1015, connector 1202, the line vertical magnet 316, test horizontal magnet 310 and the vertical magnet 212. The connection originally started is thus wiped out when the called subscriber's line is found to be busy.

When magnet 212 releases, it causes the release of relay 930 which, in turn, releases

relay 927. Relay 927 again connects the test relays to the test conductors leading to the incoming frame. Relay 911 closes a circuit for relay 906 which may be traced from battery through the winding of the latter relay, outer left contact of relay 911, outer right contact of relay 930 to the grounded conductor 932. Relay 906 locks to the conductor 913. Relay 906 operates the magnet 210 on the incoming selector by means of the circuit from battery, through the winding of said magnet, thence through the frame connector 1000, left back contact of relay 950, inner left contact of relay 911, inner right contact of relay 906 to the grounded conductor 913. The magnet 210 prepares the contacts in the row 202 which is reserved for the purpose of connecting the tone coil 221 to the incoming trunks. Magnet 210, in operating, operates the relay 930 in a manner similar to that discussed in connection with the magnet 212. Relay 930 operates the relay 928 in the manner described provided the horizontal link 205 is idle. Relay 928 closes a circuit for operating the horizontal magnet 217 as described hereinbefore which may be traced over conductor 940 through the left contacts of relays 906 and 905, inner right front contact of relay 906 to the grounded conductor 913. As soon as the time measuring relays 942 and 943 function, the marker is released. When relay 905 operates in series with relay 928 a circuit is closed from battery through the winding of slow-to-release relay 943, back contact of relay 942, left contact of relay 905, contact of relay 906 to the grounded conductor 913. Relay 943 closes an obvious circuit for relay 942 which operates and locks to conductor 913. Relay 942 opens the circuit of relay 943 which releases after an interval and operates the relay 903 as follows: battery, through the winding of relay 903, inner contact of relay 943, left front contact of relay 942, left contact of relay 905, inner right contact of relay 906 to grounded conductor 913. Relay 903 causes the release of the marker in a manner hereinbefore described. The tone apparatus 221 is now connected to the trunk 110 and a busy tone is produced in the calling subscriber's receiver, notifying him that the called subscriber's line is busy. The tone apparatus 221 may be connected to an incoming trunk through any one of the horizontal link circuits as determined by the testing relays in the marker.

Interception of calls.

To explain the manner in which calls are intercepted it may be considered that the service for station J on the subscriber's line 318 has been discontinued. To prevent calls being made to this station, it is only necessary to make a cross connection on the dis-

tributing frame associated with the translator 1200. If, for instance, the relay 1235 represents the called subscriber's station J, then the winding of this relay is wired to the next to the upper point on the distributing frame 1221. When the connecting device 1201 is operated, therefore, the relay 1235 is energized in a circuit from battery through its winding, through contacts of the device 1200, contact of relay 1209, lower contact of relay 1206 to ground over conductor 1227.

At the time the station digits is recorded on the station's register 804, relay 829 closes an obvious operating circuit for relay 830. When relay 1235 subsequently operates, a circuit is completed for the intercepting relay 950 in the marker. This circuit may be traced from battery through the winding of said relay, conductor 952, through the contact of relay 830, conductor 831, contact of relay 1235, conductor 1237, thence to ground over conductor 1223 as previously traced.

Relay 950 at its right contact closes an obvious circuit for the line busy relay 911. Relay 911 in the manner heretofore explained, breaks down the partially established connection. In this case the vertical magnet 211 on the incoming selector switch is operated to extend the calling subscriber's line over a trunk 222 to the intercepting operator's position 224. The circuit for magnet 211 may be traced from battery through the winding thereof, thence through the frame connector 1000, conductor 1028, left front contact of relay 950, inner left contact of relay 911, and thence to ground as above traced. Magnet 211 prepares the contacts in the vertical row 203.

The test relays 920 make a test of the horizontal links in the switch 200 and a circuit is completed for the horizontal operating magnet related to the first idle link and the connection is thereby connected to the trunk 222 which leads to the intercepting operator's position 224. The operator converses with the calling subscriber and notifies him that the station J on the line 318 has been discontinued. If one or more other stations on the party line should be discontinued, the distributing frame is wired so as to cause the operation of one or more of the relays 1235, 1238, 1239 and 1240, etc. Enough of these relays may be provided to give all possible combinations of the four different stations on a party line. By wiring these relays to the distributing frames on the translator 1200, calls to any station on any of the lines in the group of 2000 may be intercepted and routed to the operator's position 224.

It will be understood that by wiring the relays of the group 1203 in the proper manner through the translator 1200, calls to direct subscribers' lines may also be intercepted.

What is claimed is:—

1. In a telephone system, subscribers' lines, switches for making connection with said lines, a controlling mechanism common to said switches and including individual means for identifying each of said lines, selectively operable means for connecting said mechanism to any one of said switches, means controlled by said mechanism for selectively operating said switches, and means controlled by said identifying means for intercepting a call that is being extended to one of said lines.
2. In a telephone system, subscribers' lines, switches for making connection with said lines, a controlling mechanism common to said switches for governing the operation of the same, a translator common to all lines and selectively operable according to called line designations for identifying any one of said lines, selectively operable means for connecting the translator to any one of said switches, and means controlled by said translator for intercepting a call that is being extended to any one of said lines.
3. In a telephone system, subscribers' lines, switches for making connection with said lines, a plurality of controlling markers, a translator common to all of said lines and selectively operable in accordance with the designations of called lines for identifying any one of said lines, means for connecting the translator to any one of said markers for the purpose of selectively controlling the operation of said switches, an operator's position, and means controlled by said translator for intercepting calls directed to a called line and for routing the same to the operator's position.
4. In a telephone system, subscribers' lines, switches for making connection therewith, a controlling mechanism common to said switches having individual means for identifying each of said lines, selectively operable means for connecting said mechanism to any one of said switches, means controlled by said mechanism for selectively operating said switches, an operator's position, and means controlled by said mechanism for intercepting a call before it has been extended to the called line and for routing the same to said operator's position.
5. In a telephone system, subscribers' lines, selective switches for making connections with said lines, a controlling mechanism common to said switches and including individual means for identifying each of said lines, means for preparing said switches for operation, means controlled by said mechanism for operating said switches to extend connections to called lines, and means controlled by said mechanism for discharging the prepared switch before the connection has been extended to certain lines, an operator's position, and means for routing the intercepted call to the operator's position.
6. In a telephone system, a plurality of lines including a party line, switches for extending connections to said lines, a controlling mechanism common to said switches and provided with means for individually identifying each of said lines, means controlled by said mechanism for selectively operating said switches, an operator's position, and means controlled by said identifying means for intercepting a call that is being extended to a station on said party line and for routing the same to the operator's position.
7. In a telephone system, subscribers' lines including party lines, a translator mechanism common to said lines and having means for identifying each of said lines individually, a group of relays operable from said translator in combination to represent any station or stations on any party line, an operator's position, and means controlled by said relays for intercepting calls to the stations on party lines and for routing such calls to the operator's position.
8. In a telephone system, subscribers' lines, a connector switch for extending connections to said lines, a translator common to all lines and having means for identifying each line individually, said translator normally being disconnected from the connector switch, means for operating said switch, and means controlled by said translator when a call is being directed to one of said lines for intercepting said call before the connector switch has operated to extend the connection to such called line.
9. In a telephone system, a plurality of lines including a party line, switches for extending connections to said lines, said party line having a single numerical appearance in only one of said switches, a controlling mechanism common to said switches and provided with means for individually identifying each of said lines, means controlled by said mechanism for selectively operating said switches, and means controlled by said identifying means for intercepting a call that is being extended to a station on said party line.
10. In a telephone system, a plurality of party lines, switches for extending connections to said lines, each line appearing in only one switch and having only one numerical appearance in such switch, a translator common to all switches having individual means for identifying each station on any line, means controlled by the translator for operating one of said switches, and means controlled by said identifying means for intercepting a call that is being extended to a station on one of said lines.
11. In a telephone system, incoming lines divided in groups, outgoing lines, a selective switch having links for interconnecting the lines.

said incoming lines and said outgoing lines, said links being arranged in groups according to the grouping of said incoming lines, a testing device for making a separate test of said links and outgoing lines, and means for selectively connecting said test device to any group of links in such switch.

12. In a telephone system, incoming lines divided in groups, outgoing lines, a selective switch having links for interconnecting said incoming and outgoing lines, said links being arranged in groups according to the grouping of said incoming lines, means for extending a connection over one of said incoming lines, a marker for making a separate test of said link circuits and said outgoing lines before operating the switch, and means for selectively connecting the marker to the particular group of links in which appears the trunk over which the connection has been extended.

13. In a telephone system, incoming lines, outgoing lines, a plurality of selective switches each having links for interconnecting said incoming and outgoing lines, said incoming lines being arranged in groups, the link circuits of each switch being arranged in groups corresponding to the grouping of said incoming lines, a marker common to all of said switches for making a test of the links and outgoing lines before operating the switch, and means for selectively connecting said marker to any group of links on any one of said switches.

14. In a telephone system, telephone lines, selective switches, means for controlling the selective operation of said switches to extend a connection to one of said lines, a signaling device for giving a signal over said connection, and means responsive to the busy condition of the telephone line for disestablishing the extended connection and reestablishing the same to said signaling device.

15. In a telephone system, telephone lines, selective switches, means for controlling the operation of said switches to extend a connection to a called one of said lines, a signaling device for giving a busy signal over said connection, and means responsive to the busy condition of the called line for disestablishing the extended connection and for reoperating one of said switches to extend such connection to said signaling device.

16. The combination in a telephone system

of subscribers' lines, selective switches, means for controlling the selective operation of said switches to extend a connection to a called one of said lines, a signaling equipment for giving a signal over the extended connection, and means responsive to the busy condition of the called line for releasing certain of said switches to partially disestablish the extended connection and for reoperating one of said switches to extend such connection to said signaling equipment.

17. The combination in a telephone system of telephone lines, selective switches, a register controlling device for governing the selective operation of said switches to extend a connection to a called one of said lines, a signaling device, and means in said controlling device responsive to the busy condition of the called line for causing the partial release of the extended connection and for reoperating one of said switches to seize said signaling device for transmitting a busy signal over the extended connection.

18. The combination in a telephone system of a subscriber's line, a selective switch having access to said line, a second switch for extending connections to said first switch, a register controlling mechanism for governing the selective operation of said switches to establish a connection through said switches to the subscriber's line, a signaling device for giving a signal over the extended connection and appearing in contacts of said second mentioned switch, means effective when the subscriber's line is busy for causing the release of said switches to disestablish the connection extended therethrough and for reoperating said second mentioned switch to seize said signaling device.

19. The combination in a telephone system of an incoming line, a selective switch having a plurality of link circuits, an outgoing line appearing in said switch, means for controlling the selective operation of said switch to extend said incoming line over one of said link circuits to said outgoing line, a signaling device appearing in said switch, and means for causing the operation of said switch to extend the incoming line over one of said link circuits to said signaling device.

In witness whereof, I hereunto subscribe my name this 19th day of March, A. D. 1924.

SAMUEL B. WILLIAMS.
